[57] CLAIM

The ornamental design for a curtain rod, as shown and described.

DESCRIPTION

FIG. 1 is a front elevational view of our new design for a curtain rod;

FIG. 2 is a top plan view thereof;

FIG. 3 is a left side elevational thereof;

FIG. 4 is a right side elevational thereof;

FIG. 5 is a rear elevational view thereof; and

FIG. 6 is a bottom view thereof.

The rod shown in FIGS. 1, 2, 5, and 6 is broken away in each figure to indicate indeterminate length.

FIG. 2

FIG. 3

FIG. 1

FIG. 4

FIG. 5

FIG. 6
